Atty.

UNITED STATES PATENT OFFICE.

THOMAS E. BARNUM, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR CONTROLLER.

Application filed May 17, 1920. Serial No. 381,862.

This invention relates to motor controllers and more particularly to combined starting and low-current cutout controllers for alternating current motors having different circuit connections for starting and running, such for example as motors of the split phase single phase type, although certain features of the invention may be advantageously used in other relations.

For facilitating starting of motors of the aforesaid character it is customary to provide the same with special starting windings adapted to be de-energized during normal running and the present invention has among its objects that of providing a simplified controller for effecting starting commutation of the circuit connections of such motors.

Another object is that of providing a controller of the character stated which may be actuated voluntarily to provide both starting and running connections for the motor and to de-energize the same, and which is furthermore adapted following release thereof when in starting relation to automatically assume and maintain a relation suitable for running.

Another object is that of providing a controller of the character aforesaid wherein provision is made for de-energizing the motor automatically upon failure of current.

Other objects and advantages will herein-after appear.

In the accompanying drawing, wherein is illustrated an embodiment of the invention,

Figure 1 is a front elevational view partly in section thereof;

Fig. 2 is a side elevational view also partly in section of the same; while,

Fig. 3 is a diagrammatic view illustrating certain proposed circuit connections therefor.

Referring to the drawing, the same illustrates two pairs of relatively spaced fixed contacts 5, 6 and 7, 8 adapted when jointly bridged to provide starting circuit connections for the controlled motor whereas the latter pair alone are adapted when bridged to provide running connections therefor. A movable bridging contact 9 is carried by a pivoted contactor arm 10 and movable thereby to three definite positions, viz., an extreme position for bridging both pairs of

fixed contacts, an intermediate position wherein only the running contacts are bridged, and an opposite extreme position wherein both pairs of fixed contacts are disengaged and the motor de-energized. An operating handle 11 provides for manual setting and holding of said contactor arm and bridging contact in any of the aforementioned positions while a spring 12 serves to bias said parts for movement of said bridging contact away from said fixed contacts.

An electromagnet 13, having a pivoted armature 14 loosely connected to said contactor arm, serves when energized to hold said arm in its intermediate position, said loose connection permitting movement of said arm to its extreme contact making position, whereas for movement of said arm to its contact disengaging extreme position said arm and the armature 14 are adapted to be forced outwardly by means of said operating handle.

More specifically, each of said fixed contacts comprises a conductive metallic strip having a contacting portion and a portion bent substantially at right angles to the main portion thereof for securement to a base 15, such securement being effected by means of bolts 16 or in any suitable manner. The contacts 7 and 8 are adapted to project forwardly from the base a greater distance than the contacts 5 and 6 to provide for engagement of said former contacts by the movable contact when in its mid-position.

The contactor arm 10 comprises a substantially flat member having lugs 17 bent substantially at right angles thereto and having at their free ends openings to receive a shaft 18, the latter being secured in place by means of cotter pins or otherwise and being adapted to carry between said lugs a hollow substantially cylindrical conductive member which constitutes the movable contact 9, said contact being in practice insulated from the shaft 18 by means of an intermediately located sleeve 19 and from the lugs 17 by means of end washers 20.

The electromagnet 13 comprises a frame 21 to be rigidly secured to the base 15 below the fixed contacts carried thereby, said frame having a rigidly secured core member 22 and forwardly projecting upper and lower pole pieces 23 and 24 providing a channel adapt-

ed to receive the electromagnetic winding 25. Said lower pole piece 24 is provided with spaced downwardly projecting lugs 26 having aligned openings to receive a shaft 27 which in practice may be formed integral with the operating handle 11. The lower end of the contactor arm 10 is rigidly secured to a medial portion of said shaft 27 for movement therewith. The spring 12 is coiled about a portion of said shaft adjacent said contactor arm, one of the projecting ends of said spring being adapted to abut a portion of the magnet frame and the opposite end of said spring being adapted to abut a suitable lug 28 upon said contactor arm for biasing the latter outwardly as described.

The armature 14 is provided with backwardly extending lugs 29 for loose mounting thereof upon the shaft 27. A projecting stud 30 is rigidly secured to a central portion of said armature and adapted to extend through an opening 31 in the contactor arm being provided with spaced shoulders 32 and 33 on either side of said arm for permitting a limited relative movement of said elements. In practice the opening 31 in said contactor arm is preferably of keyhole formation having an enlarged upper portion through which the head of the stud 30 may be inserted during assembly and a reduced lower portion adapted to be occupied by the reduced portion of said stud when in normal position.

The afore-described parts are enclosed within a suitable housing comprising a flat top section 34 and a separate section 35 providing the bottom, front and sides of the housing. Said top section is provided with an upturned flange 36 for permanent securement thereof to the base 15 by means of bolts 37. The section 35 is provided at the top thereof with a backwardly turned flange 38 adapted to fit above the front edge of the section 34 to provide for support of said section 35 and also provide a substantially dust proof joint. Said section 35 is in practice secured to the base 15 by means of an elongated screw bolt 39 accessible for removal from the front of the housing.

A bushing 40 having a conduit clamp 41 is screwed within the top section 34 of the housing while a separable connector 42 is also mounted upon said housing section, said bushing and said connector providing for introduction of the necessary circuit connections within the housing. In practice, assuming the controller to be mounted in proximity to the controlled motor, the motor leads are preferably brought within the housing through the bushing 40 and the line connections made through the separable connector 42 as illustrated in Figure 3, although obviously for different installations this arrangement may be varied. From inspection

of Figure 3, it is also apparent that the winding 25 of the holding magnet is arranged to be energized only by the running current of the motor.

In operation, the handle 11 is moved 70 against the bias of the spring 12 to bring the contactor arm to its extreme contact engaging position wherein both pairs of fixed contacts are bridged by the movable contact 9 and consequently both the starting and running windings of the motor. When the motor has accelerated to a suitable speed the operating handle is released whereupon the contactor arm moves to its mid-position under the bias of the spring 12 whereas the 80 armature 14, being now attracted and held against the frame member 23, serves by means of the connection aforescribed to hold said contactor arm in such mid-position for maintaining the contact 9 in such relation as to bridge only the running contacts.

In order to stop the motor, sufficient force is applied to the operating handle to overcome the attraction of armature 14 and move the same and the contacting arm 10 to their 90 extreme outer position.

Should the supplied current at any time fail, the armature 14 is released whereupon the contactor arm at once moves to effect disengagement of the fixed contacts under 95 influence of the spring 12.

What I claim as new and desire to secure by Letters Patent is:

1. In a controller for split phase motors, the combination with a plurality of sets of 100 fixed contacts, of a single contacting member movable to electrically connect all of said contacts to establish starting connections and also movable to disengage certain of said fixed contacts to establish running connections, and operating means for said contacting member including means for holding said member in a position for maintaining said running connections subject to release under given electrical conditions. 105

2. In a controller for split phase motors, the combination with a plurality of sets of fixed contacts, of a single contacting member movable to electrically connect all of said contacts to establish starting connections and also movable to disengage certain of said fixed contacts to establish running connections, manual operating means for said contacting member, and electromagnetic means to act upon said operating means for 115 maintaining said running connections. 120

3. In a controller for split phase motors, the combination with a plurality of sets of fixed contacts, of a single contacting member movable to electrically connect all of said contacts to establish starting connections and also movable to disengage certain of said fixed contacts to establish running connections, operating means for said contacting member, and holding means for said con- 125 130

- tacting member including an electromagnetic winding to be energized upon establishment of said running connections.
4. In an electrical controller, the combination with a plurality of similar and symmetrically arranged sets of spaced contacts, of a co-operating contactor therefor, the contacts of said sets being arranged for progressive engagement by said contactor and 10 said contactor being oscillable in the plane of symmetry of said sets of contacts and being elongated in a direction normal to such plane to simultaneously engage the similarly arranged contacts of said sets, and means for 15 moving said contactor to engage all of said contacts concurrently and to disengage certain similarly arranged contacts simultaneously while maintaining engagement with other of said contacts.
- 20 5. In a controller for electric motors, the combination with a plurality of sets of fixed contacts, of a contactor movable to bridge all of the same to establish starting connections and movable to disengage certain of 25 said fixed contacts to establish running connections, operating means for said contactor, means biasing said operating means to move said contactor out of engagement with said fixed contacts and preponderating means 30 for maintaining said contactor in a position providing said running connections.
6. In a controller for electric motors, the combination with a plurality of sets of fixed contacts, of a contactor movable to an extreme position wherein all of said contacts 35 are bridged to establish starting connections, said contactor being also movable to an intermediate position wherein certain only of said contacts are engaged to establish running connections and to an opposite extreme 40 position wherein all of said contacts are disengaged for interrupting both of said connections, operating means for said contactor and means to act upon said operating means 45 for releasably retaining said contactor in said intermediate position.
7. In a controller for electric motors, the combination with a plurality of sets of fixed contacts, of a contactor movable to an extreme position wherein all of said contacts 50 are bridged to establish starting connections, said contactor being also movable to an intermediate position wherein certain only of said contacts are engaged to establish running connections and to an opposite extreme 55 position wherein all of said contacts are disengaged for interrupting both of said connections, manually controlled operating 60 means for said contactor and means to act upon said operating means for retaining said

contactor in said intermediate position while providing for voluntary actuation thereof to either of said extreme positions.

8. In a controller for electric motors, the combination with a plurality of sets of fixed contacts, of a contactor movable to an extreme position wherein all of said contacts are bridged to establish starting connections, said contactor being also movable to an intermediate position wherein certain only of 65 said contacts are engaged to establish running connections and to an opposite extreme position wherein all of said contacts are disengaged for interrupting both of said connections, operating means for said contactor 70 and means to act upon said operating means for retaining said contactor in said intermediate position while providing for automatic release and movement thereof to said latter extreme position under predetermined 75 electrical conditions.

9. In an electrical controller, in combination, a plurality of sets of fixed contacts, a co-operating contact movable to engage all of said fixed contacts concurrently and to 80 disengage the sets thereof progressively, operating means for so moving said contact including an oscillable lever, a spring biasing said lever to cause disengagement of 85 said contacts, an electro-magnet having an oscillable armature loosely connected to said lever for magnetically holding the same against the action of said spring in an intermediate position wherein certain only of 90 said fixed contacts are engaged by said movable contact while permitting independent movement of said arm to an extreme position for effecting engagement of all of said contacts.

10. In an electrical controller, the combination with sets of fixed contacts and a co-operating contact movable to engage all of the same jointly and to disengage the same progressively, of a pivoted support providing for such movement of said latter contact, 100 an electro-magnet having an oscillable armature and means for mounting said armature and said support to swing in a common plane, a stud carried by said armature to provide a loose connection with said support, said connection providing for holding 105 of said support by said armature in a position for effecting engagement of certain only of said contacts while permitting independent movement of said support for effecting 110 engagement of other of said contacts, and operating means for said support.

In witness whereof, I have hereunto subscribed my name.

THOMAS E. BARNUM.

CERTIFICATE OF CORRECTION.

Patent No. 1,659,739.

Granted February 21, 1928, to

THOMAS E. BARNUM.

It is hereby certified that error appears in the printed specification of the above numbered patent requiring correction as follows: Page 3, line 103, strike out the words "jointly and to disengage the same" and insert instead "concurrently and to disengage the sets thereof"; and that the said Letters Patent should be read with these corrections therein that the same may conform to the record of the case in the Patent Office.

Signed and sealed this 20th day of November, A. D. 1928.

M. J. Moore,
Acting Commissioner of Patents.
